Attorney

UNITED STATES PATENT OFFICE.

LEONIDAS K. MIHELAKOS, OF CHICAGO, ILLINOIS.

TIE.

1,270,645.

Specification of Letters Patent. Patented June 25, 1918.

Application filed December 5, 1917. Serial No. 205,581.

To all whom it may concern:

Be it known that I, LEONIDAS K. MIHELAKOS, a citizen of Greece, residing at Chicago, in the county of Cook and State of Illinois, have invented certain new and useful Improvements in Ties, of which the following is a specification.

This invention relates to wearing apparel and the invention has more especial reference to an improve tie and holder therefor.

The invention has for its principal object to provide a formed tie having a holder or attaching member detachably secured to the same in a manner to permit the ready removal of the same and the use of the attaching member upon other ties, as desired.

Another and equally important object of the invention is to provide a tie of the character mentioned, the attaching member of which will serve to prevent undue shifting or displacement of the same when once arranged on a collar.

Other objects will be in part obvious and in part pointed out hereinafter.

The improvements in the details and arrangement of parts will be apparent from an inspection of the accompanying drawings, in connection with the description of the same hereinafter contained, and wherein in the preferred embodiment of the invention is shown and described for the purpose of facilitating a full understanding of the same.

35 In the drawings:—

Figure 1 is a disassembled perspective showing the improved tie and a fragment of the collar for use therewith,

Fig. 2 is a rear elevation of the tie attached; portions of the collar being shown in section, and,

Fig. 3 is a vertical section through the tie.

Having more particular reference to the drawings, in connection with which like reference characters will designate corresponding parts in the several views, 1 represents the formed tie, the same, obviously being of the usual bow design. A transversely

50 disposed intermediate piece 2 formed of the same material as that from which the tie 1 is formed is secured at one end to the said tie and carries a wire loop or clip 3 upon the free end of the same, which clip is adapt-

ed to be engaged with the attaching means, 55 hereinafter more fully described. As will be readily understood, the transversely disposed piece represents the usual intermediate portion commonly formed when tying ties of the bow design.

The attaching means for the improved tie comprises a concaved strip 4 preferably formed of spring metal slotted as at 4' and having a hook member 5 arranged intermediate of the ends of the same, the said hook member, obviously, being secured to the spring plate by soldering or other means common in the art. It will be noted, in this connection, that the hook 5 is substantially square and as a consequence, permits the 60 clip 3 to be snugly engaged over the same when the transverse piece 2 is passed through the slot 4' of said strip 4. By so engaging the clip 3 of the transversely disposed piece 2 with the hook 5, the attaching 65 means of the tie will be positively secured to the same and further, the arrangement of the said transverse piece, as hereinbefore stated, is such as to give a finished appearance to the tie.

The tie when arranged on a collar is prevented from undue shifting or displacement, since, as will be understood, the hook 5 is engaged over the shank of the collar button while the sides of the said hook are 70 snugly received between the adjacent edges of the collar, which, preferably, are cut-away, as shown to advantage in Fig. 2. Hence, proper positioning of the tie during the wearing of the same will be insured at 75 all time. It is to be understood that the opposite extremities of the curved strip 4 are engaged over the opposite sides of the collar on which the improved tie is arranged, thus preventing lateral displacement of the 80 tie with relation to the same, and the breaking or wrinkling of the sides of the collar.

Manifestly, the construction shown is capable of considerable modification and such modification as is within the scope of 85 my claims, I consider within the spirit of 90 my invention.

I claim:—

1. A bow tie having an intermediate transverse piece secured at one end to the 95 same, a fastener carried by the free end of said piece, and slotted attaching means removably engaged with the transverse piece

and adapted to receive the fastening means therethrough and to be engaged by the fastener.

2. A bow tie having an intermediate transversely disposed piece secured at one end thereto, a clip secured to the free end of said piece, and slotted attaching means for removably receiving the transverse piece therethrough and adapted to receive said clip thereover.

3. In combination, a bow tie having an intermediate transverse piece secured at one end thereto, a slotted concave strip receiving said transverse piece therethrough, a clip carried on the free end of the trans-

verse piece, and a substantially square hooked portion engaged with said strip and adapted to receive the clip thereover.

4. In combination, a bow tie having an intermediate transverse piece secured at one end thereto, fastening means engaged with the free end of said piece, and attaching means having a substantially square hooked portion arranged thereon removably engaged with the transverse piece and adapted to receive said fastening means over the squared hook portion.

In testimony whereof, I affix my signature hereto.

LEONIDAS K. MIHELAKOS.
